Primary Examiner—Kay H. Chin**[57] CLAIM**

The ornamental design for the garden dolly, as shown and described.

DESCRIPTION

FIG. 1 is a perspective view of the garden dolly showing my new design;

FIG. 2 is a front elevational view thereof;

FIG. 3 is a side elevational view thereof;

FIG. 4 is top plan view thereof; and,

FIG. 5 is a bottom plan view thereof.

The broken lines shown in FIG. 2 are for illustrative purposes only and from no part of the claimed design.
